UNITED STATES PATENT OFFICE.

JOHN E. ERICKSON AND WALTER F. ERICKSON, OF ST. PAUL, MINNESOTA.

LIQUID-FUEL BURNER FOR HEATING PLANTS.

Application filed November 17, 1923. Serial No. 675,319.

To all whom it may concern:

Be it known that we, JOHN E. ERICKSON and WALTER F. ERICKSON, citizens of the United States, residing at St. Paul, in the county of Ramsey and State of Minnesota, have invented certain new and useful Improvements in Liquid-Fuel Burners for Heating Plants, of which the following is a specification.

Our invention relates to liquid fuel burners for heating plants, and an object is to provide a device of this character which will form a highly combustible mixture of vaporized liquid fuel and heated air for burning in the firebox of the heating plant. An object in particular is to provide a device in which all of the air which is drawn into the burner to support combustion is pre-heated, this pre-heated air being employed to vaporize the liquid fuel as it is delivered to the zone of combustion. Another object is to provide means for regulating the amount of preheated air which is delivered. Another object is to provide means in connection with a liquid fuel supply tank whereby the liquid fuel may be dropped in regulated quantity for passage to the burner.

The full objects and advantages of our invention will appear in connection with the detailed description, and the novel features of our inventive idea will be particularly pointed out in the claims.

In the accompanying drawings which illustrate a practical form in which our invention may be embodied, Fig. 1 is a view of the device mostly in vertical central section. Fig. 2 is a view in horizontal section on the line 2—2 of Fig. 1. Fig. 3 is a view in horizontal section on the line 3—3 of Fig. 1.

Referring to the drawings, the numeral 10 designates the firebox of a furnace or other heating plant. Located in this firebox is a burner which is preferably in the form of a casting in two or more parts, and includes a plate member 12 on the underside of which are a number of sockets 14 which adjustably receive cylindrical members 16 constituting legs for supporting the burner on the floor or base of the heating plant. The central portion of the plate 12 is raised and this raised portion is provided with a central opening. Surrounding this opening and placed upon the upper surface of the raised portion is a disk member 18

preferably of brass. The underside of the raised portion is socketed for receiving the upper end of a tube 20, the lower end of which is closed by a cap 22 so that the tube 60 constitutes a well for liquid fuel. Two sets of tubes having open lower ends extend up through openings in the plate 12, there being four tubes for each set in the embodiment as shown. The tubes of one set which are designated by the character 24 are connected with the upper portion of a cylindrical casting 26 so as to open into the space therein; the tubes of the other set which are designated by the character 28 are connected with the lower portion of the casting 26 so as to open into the space therein. An annular member 30 rests upon the periphery of the plate 12 so as to close the space between the latter and the interior 75 wall of the furnace. The member 30 in effect constitutes a continuation of the plate 12 but for convenience in fitting the burner in the firebox, it is shown as a separate piece. The plate 12 and its extension 30 80 form a substantially air-tight bottom for the firebox so that the air for supporting combustion is forced to go through the tubes 24 and 28 whereby it is pre-heated. A cone-shaped deflector 31 rests upon the tops of the tubes 24 so as to deflect the flame in the firebox 10 toward the wall of the furnace. The top of the cylinder 26 is fitted with a plug 32 having a central opening through which a hollow stem 34 extends slidably. The upper end of the stem 34 is closed by a removable plug 35. Secured to the lower end of the stem 34 which is split is a ring-like damper 36 having sliding engagement with the inner wall of the cylinder 26. For operating the damper 36, a lever handle 38 is pivotally attached to the upper end of the stem 34. One end of the lever 38 is pivotally attached to a post 40 which extends up from the plug 32. Extending up from the plug 32 diametrically opposite the post 40 is a segment 42 having a number of recesses adapted to be engaged by a catch 44 on the lever 38. The movable end of this lever extends through a slot 46 in the deflector 31. Connected with the lower portion of the well tube 20 is a horizontal pipe 48 which is connected to a vertical upwardly extending pipe 50 attached to the upper end of which is a funnel-shaped member 52. Resting upon the upper end of the member 52 is a glass cylinder 54 which constitutes

a sight-feed device. A head member 56 is held upon the upper end of the cylinder 54 by rods 58 which connect the head with the funnel member 52. The head member 56 has a hollow enlargement 60 forming a chamber which is connected by a perforation 62 with the sight-feed device. Extending horizontally from the enlargement 60 is a hollow stem 64, the passageway 10 through which is controlled by a needle valve 66. The stem 64 is connected by a pipe 68 with a supply tank 70. The head 56 is provided with an air-pipe 72 so that as the liquid fuel drops through the sight- 15 feed device air is drawn in through this pipe for mixing with the liquid fuel. The plate 12 is provided with an annular rib 74 which forms a catch basin for liquid fuel overflowing in case the burner goes 20 out. A pipe 76 leads from the catch basin for conducting the overflowing fuel to any suitable receptacle.

The operation and advantages of our invention will now be readily understood. 25 When the burner is to be used, the needle valve is opened sufficiently to allow the liquid fuel to drop at the desired rate through the sight-feed device, air being drawn in through the pipe 72 by the falling 30 liquid, and this adds to the efficiency of the burner. The well tube 20 being full of the liquid fuel, the dropping of the liquid fuel will cause an overflow upon the brass disk 18. The provision of a brass disk reduces 35 the tendency to form a deposit of carbon. As soon as the fuel which flows upon the disk 18 is ignited, the flame passes out under the damper 36, around the tubes 24 and 28, and is spread out by the deflector 31. All 40 of the air which supports the combustion except that which enters the sight tube device is supplied through the tubes 24 and 26 which are highly heated with the result that the fuel on the brass disk 18 is vaporized, this vapor being burned outside the 45 limits of the disk. A large quantity of highly heated air is drawn in by the suction produced by the flame with the result that a hot flame is produced with a small supply 50 of liquid fuel. The amount of air drawn in is regulated by the position of the damper 36 and the amount of liquid fuel supplied is regulated by the position of the needle valve 66. The burner is so constructed that it may 55 be readily installed in furnaces and other heating plants now in use. In order to more effectively clean the burner, the cap 22 and the plug 35 may be removed, thereby producing an open vertical passageway through 60 the burner.

We claim:

1. In combination with the firebox of a heating plant, a platelike partition which

forms the bottom of the firebox, said partition having a raised central portion with 65 an opening therein, a well tube secured to said raised portion underneath said opening, a plurality of tubes extending up through said partition and passing through the zone of combustion, a cylindrical member to 70 which the upper ends of said tubes are connected for supplying preheated air thereto, said cylindrical member being spaced above the raised portion of said partition, a ring- 75 like damper slidably mounted at the lower 80 end of said cylindrical member, means whereby said damper may be raised and lowered to regulate the amount of preheated air which passes out of the bottom of said cylindrical member, a deflector mounted at 85 the top of said cylindrical member, and means for supplying liquid fuel to said well tube.

2. In combination with the firebox of a heating plant, a partition which forms the 85 bottom of the firebox, said partition having a raised central portion with an opening therein, means for supplying liquid fuel to said opening, an annular rib on said partition surrounding said raised portion whereby a catch basin is produced, a pipe leading from said catch basin, a plurality of tubes extending up through said partition and passing through the zone of combustion, a cylindrical member to which the upper ends 95 of said tubes are connected for supplying preheated air thereto, said cylindrical member being spaced above the raised portion of said partition, a ringlike damper slidably mounted at the lower end of said cylindrical member, and means whereby said damper may be raised and lowered to regulate the amount of preheated air which passes out of the bottom of said cylindrical member. 100

3. In combination with the fire-box of a heating plant, a partition which forms the bottom of the fire-box, said partition having a central opening therein, means for supplying liquid fuel to said opening, a plurality of tubes extending up through said partition around said opening and passing through the zone of combustion, a cylindrical member to which the upper ends of said tubes are connected for supplying preheated air thereto, said cylindrical member being spaced above said partition, a ring-link damper slidably mounted at the lower end of said cylindrical member, and means whereby said damper may be raised and lowered to regulate the amount of preheat- 115 ed air which passes out of the bottom of said cylindrical member. 120

In testimony whereof we hereunto affix our signatures.

JOHN E. ERICKSON.
WALTER F. ERICKSON.
